UNITED STATES PATENT OFFICE.

DAWSON M. HUMISTON, OF TONICA, ILLINOIS.

GLAZIER'S HAMMER.

SPECIFICATION forming part of Letters Patent No. 703,790, dated July 1, 1902.

Application filed September 26, 1901. Serial No. 76,714. (No model.)

To all whom it may concern:

Be it known that I, DAWSON M. HUMISTON, a citizen of the United States, residing at Tonica, in the county of La Salle and State of Illinois, have invented certain new and useful Improvements in Glaziers' Hammers; and I do hereby declare the following to be a full, clear, and exact description of the invention, such as will enable others skilled in the art to which it appertains to make and use the same.

This invention relates to that class of driving-tools by which the brads known as glaziers' "points" are driven into the sash by blows of an instrument held in the hand and sliding on the pane of glass.

The object of the invention is to produce a tool by which to force the pane of glass to position should it bind in the sash and to drive the brads or "points," so-called, by which the glass is held until secured by putty.

Figure 1 is a side elevation of the improved hammer, showing in dotted lines the parallel position of head with handle. Fig. 2 is a plan of the hammer. Fig. 3 is a face view 25 of the hammer with handle partly broken away. Fig. 4 is a broken end view of hammer-head enlarged. Fig. 5 is a broken edge view of the hammer-head enlarged. Fig. 6 is a perspective showing the general relation 30 of the hammer to the point or brad in driving, the inclination of the handle being somewhat exaggerated.

The hammer-head 1, as shown, is a rectangular block of metal, having a generally flat rim 2 around its face, but recessed at its central portion 3, so that the recess incloses a body of air and forms an air-cushion to protect the glass from breakage when the hammer is dropped or falls quickly on a pane of 40 glass.

Two ears or lugs 4 project from the back of the head, and a hole 5 is bored through these lugs in direction parallel with the plane of the face of the hammer.

A handle-bar 6 has its end 7, as shown, provided with a fork, and this forked end fits between the lugs 4 of the hammer-head. The end 8 of the handle-bar or the forked tines thereof should be beveled at about an angle 50 of thirty degrees, more or less. The forked bar is bored transversely and a pin 10 passes through the lugs on the hammer-head and

the holes in the handle-bar. The hammer-head may thus rock on this pivot to any position between a position parallel with the 55 handle-bar, as shown in dotted lines, Fig. 1, and a position in which it is stopped by engagement with the beveled end of the handle-bar, as shown in full lines in the same figure.

A sleeve 11 may surround the pin 10 between the forked tines of the handle-bar. The particular manner of pivoting the head to the handle-bar, however, is not considered very important. The essential idea is that the head is pivotally connected to the handle 65 preferably about opposite the center of gravity of the head, so that the head will be balanced and tend to remain in any position to which it may be turned on its pivot and that the pivotal movement of the head be 70 limited in both directions about as stated.

The polygonal head has straight sides, and these sides are grooved near the bottom edge, the grooves running parallel with the plane of the face. The grooves or rabbets 13 are 75 for the purpose of holding down glaziers' points or triangular brads of sheet metal. The body of the hammer-head thus slightly overhangs the brads when the brads lie flat on the glass, and the hammer slides along on 80 the surface of the glass to drive such brads into the sash.

The handle-bar 6, as illustrated, tapers to a thin edge 15, the bar preferably having the outer edges parallel. This edge forms a very 85 efficient tool for "keying up"—that is, forcing a pane of glass to proper position in the sash when for any reason there is a tendency to bind.

A wooden or other suitable handpiece 16 is 90 applied to the handle-bar and secured thereon by the close fit of the perforated handpiece to the tapered bar or in other suitable manner. The rounded end 17 of this handpiece is toward the point or edge 15 of the 95 handle-bar. Said point or edge projects, say, about one and one-half inches from the rounded end of the handpiece, and this rounded end forms a convenient fulcrum when the end or point 15 is used as a lever.

The hammer is used in driving glaziers' brads or points by placing the face of the hammer-head flat on the pane of glass, on which the points or triangular brads of sheet

metal also lie flat. The handle is held at such convenient angle as permits free movement of the hand. With a sliding blow the brads or points are driven into the sash or sash-bar, 5 the rabbet or overhang preventing the rise of the outer end of the point or brad when it is struck by the hammer. The direction of the blow is sidewise with reference to the hammer-head, and a blow can be struck in either 10 direction—that is, with either side of the hammer.

The straight side of the hammer-head when it bears against the triangular brad or point lying on the face of the pane of glass causes 15 the point to assume the proper position so that its sharp end is presented directly to the sash or sash-bar, and by a light sliding blow from the hammer-head the said point or brad is driven into the sash, lying snugly against 20 the glass.

What I claim is—

1. A glazier's hammer having a head with straight sides, and a handle pivoted to said

head, the pivotal movement of the head relatively to the handle being limited in both directions by engagement of the parts. 25

2. A glazier's hammer having a handle and a head with a straight side, the side having a groove parallel with and near to the face.

3. A glazier's hammer having a handle and 30 a head with a rim in a plane around its face, and a recess or air-cushion inside said rim, substantially as described.

4. A glazier's hammer having a head polygonal in outline, a handle pivotally connected 35 to the back of said head, means for limiting the pivotal movement of the head relatively to the handle, and grooves in the sides of said head.

In testimony whereof I have signed my 40 name to this specification in the presence of two subscribing witnesses.

DAWSON M. HUMISTON.
